CLAIM

The ornamental design for a shower curb cap, as shown and described.

DESCRIPTION

FIG. 1 is a perspective view of a shower curb cap showing the design;

FIG. 2 is a top plan view of the shower curb cap of FIG. 1; FIG. 3 is a bottom plan view of the shower curb cap of FIG. 1;

FIG. 4 is a right elevational view of the shower curb cap of FIG. 1;

FIG. 5 is a left elevational view of the shower curb cap of FIG. 1;

FIG. 6 is a front elevational view of the shower curb cap of FIG. 1; and,

FIG. 7 is a rear elevational view of the shower curb cap of FIG. 1.

The dash-dash broken lines in the drawings depict portions of the shower curb cap that form no part of the claimed design. The dot-dash-dot broken lines in the drawings define the boundaries of the claim and form no part thereof.
